UNITED STATES PATENT OFFICE.

EDWARD C. WOODWARD, OF BROCKTON, MASSACHUSETTS, ASSIGNOR OF
TWO-THIRDS TO ELLERY C. WRIGHT AND HORACE F. WOODWARD,
BOTH OF SAME PLACE.

LAST.

SPECIFICATION forming part of Letters Patent No. 398,923, dated March 5, 1889.

Application filed November 23, 1888. Serial No. 291,699. (No model.)

To all whom it may concern:

Be it known that I, EDWARD C. WOODWARD, of Brockton, county of Plymouth, State of Massachusetts, have invented an Improvement in Lasts, of which the following description, in connection with the accompanying drawings, is a specification, like letters on the drawings representing like parts.

The last contained within a boot or shoe when being heeled in usual manner is held in position by a pin or tool entering a pin or tool receiving hole formed in the heel portion of the last. The great pressure exerted upon the last by the machine often acts to split the last, to avoid which a metallic thimble has been placed in the pin or tool receiving hole, and the thimble has had its lower end closed to resist the pressure; but with such thimble the great pressure against the closed end of the thimble breaks the same through.

This invention has for its object to provide a strong and durable support or bearing-surface within the last and coincident with the pin or tool receiving hole, against which support the pin or tool of the heeling or other machine may strike or bear and find a rigid bearing.

In accordance with this my invention an independent bar-like support is embedded in the last intersecting the pin or tool receiving hole at right angles, and when a metallic tube is fitted in said hole it bears directly upon the said support. To place the said bar-like support in position, I preferably bore a hole into the side of the last at right angles to the pin or tool receiving hole and place the said bar-like support in said hole, and thereafter either fit a plug into the hole to leave a finished or smooth surface, or, if desired, finish the end 40 of the bar.

Figure 1 shows in longitudinal section a last provided at the base of the pin or tool receiving hole with a bar-like support made in accordance with this invention; Fig. 2, a vertical section of the last, taken on the dotted line xx , Fig. 1, and Fig. 3, a longitudinal section of the last provided with a modified form of support at the base of the pin or tool receiving hole.

50 The last-body a is provided at the heel por-

tion with a pin or tool receiving hole, into which is snugly fitted the metallic tube b . A hole, as c , is bored or formed in the heel portion of the last intersecting the pin or tool receiving hole at right angles. A bar-like support, herein represented as a metallic block, d , having a flat upper face, is placed in said hole c , so that the tube b bears directly upon the flat face of the said block. A block of wood or other material, d' , is then fitted into the hole c and finished flush with the surface of the last.

Fig. 3 shows a cylindrical support, d , in lieu of the flat-surfaced block in Fig. 1. The lower end of the tube b will be cut away to bear directly on this block or bar.

The support herein shown constitutes a rigid as well as an enlarged or laterally-extended bearing to resist the great or excessive pressure of the pin or tool entering the pin or tool receiving hole, and also resisting pressure which may be brought to bear on the metallic tube.

I claim—

1. The last having the pin or tool receiving hole, and having a block-receiving hole in its body intersecting the said tool-receiving hole, combined with a metallic bar-like support inserted in the said block-receiving hole at the end of the tool-receiving hole, the said block 80 constituting a rigid bottom within the body of the last for the tool to abut against, substantially as described.

2. The last having the pin or tool receiving hole, and having a block-receiving hole in its body intersecting the said tool-receiving hole, and a metallic tube placed in the said tool-receiving hole, combined with a metallic bar-like support inserted in the said block-receiving hole at the end of the tool-receiving hole, 90 the said block constituting a rigid bottom within the body of the last for the tool to abut against, substantially as described.

In testimony whereof I have signed my name to this specification in the presence of two subscribing witnesses.

EDWARD C. WOODWARD.

Witnesses:

JOHN F. ALLEN,
IRA A. LEACH.
